UNITED STATES PATENT OFFICE

2,633,146

FUEL PULSATION DAMPENER AND
PRESSURE REGULATOR

Joseph B. Witt, Fairfield, Ill.

Application March 21, 1947, Serial No. 736,348

2 Claims. (Cl. 137—479)

1

This invention relates to improvements in automatic fuel pulsation dampener and pressure regulator, particularly adapted, though not necessarily limited in use with internal combustion engines, for controlling the fuel pressure at the carburetor, according to the pull which the motor or engine is subjected to under various throttle openings of the carburetor, causing the pressure delivered against the inlet valve (needle valve) of the carburetor to be at a minimum when the motor is idling or under a light pull, and to automatically cause the pressure at that point to increase to the maximum as the motor is subjected to a maximum pull, or throttle opening.

Another object is to provide a device of this character, which will eliminate the jiggling or hammering action of the needle valve against the needle valve seat and float lever in the carburetor, which is caused by the pulsating action of the fuel pumps, thereby reducing wear on the carburetor, and giving more carburetor protection.

A further object is to provide an improved automatic pressure regulator which is incorporated in a filter-damper, and which will result in fuel economy and an elimination of flooding troubles, caused by high pressure at the carburetor, whether such flooding is caused from a high pressure fuel pump, or is due to other reasons, such as expansion of fuel in the gas line, due to heat, etc.

A still further object is to provide an improved device of this character, which is operated by the vacuum from the motor, a high vacuum operating to lower the pressure at the carburetor, thereby causing the fuel level in the carburetor to be lowered, thus causing a leaner mixture when the vacuum is high, or when the motor is not under a heavy load.

To the attainment of these ends, and the accomplishment of other new and useful objects as will appear, the invention consists in the features of novelty in substantially the construction, combination and arrangement of the several parts, hereinafter more fully described and claimed, and shown in the accompanying drawing illustrating this invention, in which:

Fig. 1 is a side elevation of the chassis of a motor vehicle, showing this invention applied thereto.

Fig. 2 is an enlarged view, in elevation, of this improved automatic pulsation dampener and pressure regulator unit.

Fig. 3 is a vertical sectional view on line 3—3, Fig. 2.

2

Fig. 4 is a detail perspective view of the flexible diaphragm, and the valve operating link or member attached thereto.

Referring more specifically to the drawing, the device consists essentially of a body portion 10, having an inlet opening 11, to which a pipe 12 is connected, and an outlet 13, to which a pipe 14 is connected. A sediment bowl or chamber 15 is secured to the body, preferably by means of a yoke or bail 16 pivoted to the body, as at 17, and which passes under the bowl. A screw 17a is carried by the yoke, and projects into a spacing cap 18, which engages the bottom of the bowl. Adjustably carried by the screw is a nut or collar 19, that is adapted to be moved into contact with the cap 18, whereby to secure the bowl 15 removably in position.

Arranged within the bowl to extend thereacross, is a steamer or filter screen 20, which is provided with an opening 21a, arranged to communicate with the inlet end 21 of the outlet pipe 14, so that the fuel, before entering the passage 13, must pass through the screen. The filtering screen is also arranged in alignment with, and extends across, the outlet end 22a of the inlet pipe 12, so that the fuel entering the pipe 12 will flow through the screen into the bowl 15, which latter constitutes a sediment chamber and reservoir. From the chamber, the fuel, after being filtered, will flow through the screen and into the outlet pipe 14. The screen is held in position in any suitable manner, preferably by the periphery thereof being clamped or gripped between the edge of the bowl and the gasket or sealing ring 19.

A cap member 22 is secured in position in any suitable manner, such as by means of screws or bolts 23, and between the cap member 22 and the body portion 10, is disposed a flexible diaphragm 24 that has secured to it on opposite sides thereof, protector plates 25. Secured to and depending from the diaphragm, is a valve operating link or member 26, which is provided with a laterally projecting arm or extension 27, having an opening 28 therein.

The member 26 is of a length to extend below the body portion 10, and a valve 29 having a projection 30, is carried by said extension 27, the valve being held in position with respect thereto by the projection 30 being seated in the opening 28. This valve controls the outlet end of the passage 11, by abutting the end thereof, which forms a seat for the valve. The rounding or circular shape of the projection 30 adapts the valve to rock with respect to its seat formed by

the edge of opening 28, so as to accurately abut the seat at the outlet end of the inlet passage 11.

An adjusting screw 31 is threaded into the cap member 22, and a coil spring 32 is seated in the cap member, with one end abutting the protector plate 25 on the diaphragm 24, and the other end engaging the adjusting screw 31. The movement of the diaphragm is influenced by engine suction, and by adjustment of the screw 31. The degree of engine suction to actuate the diaphragm, and the extent of such actuation of the diaphragm, may be varied, as such adjustment will vary the stress of the spring 32 with respect to the diaphragm.

The space 33 above the diaphragm constitutes an air space, and a vent opening 34 is provided to balance the vacuum. The vent opening preferably passes through the screw 31, and communicates with said air space.

When the device is installed, the inlet pipe 12 is connected with a fuel pump 35, which receives its supply from a tank 36, through a pipe 37. The outlet pipe 14 is connected to the carburetor 38. The chamber 33 on the upper side of the diaphragm 24, is connected by means of a pipe 39, to the engine intake manifold 40, so that suction in the engine will be manifested in the chamber 33, and upon the diaphragm 24, through the pipe 39, to actuate the diaphragm and thereby control the movement of the valve 27 with respect to its seat at the outlet end of the intake passage 11. Therefore, by varying the stress of the spring 32, by adjusting the screw 31, the amount of suction in the engine to actuate the diaphragm 24 and valve 27, may be varied.

By the installation of this invention in the fuel line between the pump 35 and the carburetor 38, and connecting an air line 39 from the unit to the intake manifold 40 of the engine, and routing the fuel through the unit, the fuel pressure against the carburetor inlet valve will be automatically lowered when the engine requires less fuel, and increased when more fuel is required.

In operation, the spring pressure against the diaphragm is higher than the fuel pressure against the diaphragm. When a low vacuum is created, the spring 32 forces the diaphragm 24 away, permitting the valve 27 to open, which allows higher pressure to be transmitted to the carburetor. When the vacuum is increased, it pulls the diaphragm against the spring 32, closing the valve 27, and allowing less pressure to be transmitted to the carburetor.

Without the installation of this improved unit, the pressure remains at a maximum at all times. Furthermore, by providing low pressure at the carburetor when only low pressure is required, means that at that time the fuel level in the carburetor will be lowered and a leaner mixture

will result, thus preventing waste of fuel, without damage to the engine.

While the preferred form of the invention has been herein shown and described, it is to be understood that various changes may be made in the details of construction, and in the combination and arrangement of the several parts, within the scope of the claims, without departing from the spirit of this invention.

What is claimed as new is:

1. In a device of the character described, a chamber, a diaphragm in said chamber, a fuel inlet and a fuel outlet on the same side of the diaphragm, a valve for controlling said inlet, a support connected with the diaphragm, said support having a lateral extension passing beneath the discharge end of the inlet passage, said valve being separate from and supported by said extension, means operating on said diaphragm tending normally to move it in a direction to open said valve, and connecting means adapted to connect said chamber on the opposite side of the diaphragm and the suction side of an engine, whereby the suction will move the diaphragm in a direction to close the valve.
2. In a device of the character described, a chamber, a diaphragm in said chamber, a fuel inlet and a fuel outlet on the same side of the diaphragm, a valve for controlling said inlet, a support connected with the diaphragm, said support having a lateral extension passing beneath the discharge end of the inlet passage, said valve being separate from and supported by said extension and having a projection extending into an opening in said extension, means operating on said diaphragm tending normally to move it in a direction to open said valve, and connecting means adapted to connect said chamber on the opposite side of the diaphragm with the suction side of an engine, whereby the suction will move the diaphragm in a direction to close the valve.
